(57) **CLAIM**

The ornamental design for a two-piece merchandise tag of indeterminate length, as shown and described.

DESCRIPTION

FIG. 1 is a front view of a two-piece merchandise tag of indeterminate length, showing the new design;

FIG. 2 is a front perspective view thereof;

FIG. 3 is a rear view thereof;

FIG. 4 is a rear perspective view thereof;

FIG. 5 is a front perspective view thereof, showing the two-piece merchandise tag of indeterminate length in a first alternate position;

FIG. 6 is a rear perspective view thereof, showing the two-piece merchandise tag of indeterminate length in the first alternate position;

FIG. 7 is a front perspective view thereof, showing the two-piece merchandise tag of indeterminate length in a second alternate position;

FIG. 8 is a rear perspective view thereof, showing the two-piece merchandise tag of indeterminate length in the second alternate position; and,

FIG. 9 is a side view thereof, showing the two-piece merchandise tag of indeterminate length in the second alternate position.

The two-piece merchandise tag of indeterminate length is shown broken away in FIGS. 1 through 9 of the drawings to indicate indeterminate length, it being understood that it has a uniform shape and appearance throughout its length.

The two-piece merchandise tag of indeterminate length is shown with symbolic breaks, formed by broken lines. The appearance of any portion of the article between the break lines forms no part of the claimed design.
